UNITED STATES PATENT OFFICE.

HARRY A. ROAT, JR., OF HARRISBURG, PENNSYLVANIA.

WARDROBE.

1,137,534.

Specification of Letters Patent. Patented Apr. 27, 1915.

Application filed July 16, 1914. Serial No. 851,338.

To all whom it may concern:

Be it known that I, HARRY A. ROAT, Jr., a citizen of the United States, and a resident of Harrisburg, in the county of 5 Dauphin and State of Pennsylvania, have invented a new and useful Improvement in Wardrobes, of which the following is a specification.

My invention is an improvement in wardrobes, and has for its object to provide a 10 device of the character specified, especially designed for travelers, and having mechanism for permitting it to be easily attached to a fixed support or detached therefrom, 15 and capable of folding into small compass for transportation and storage, and providing when in place protection for a number of garments of different character.

In the drawings:—Figure 1 is a perspective view of the improvement with parts 20 broken away, Fig. 2 is an enlarged section on the line 2—2 of Fig. 1, Fig. 3 is a vertical section, Fig. 4 is a face view of the supporting bar, Fig. 5 is a front view of the hat rack, Fig. 6 is a top plan view of the rigid support, and Fig. 7 is a detail perspective view of a portion of the brace.

In the present embodiment of the invention a closed supporting bracket or rack is 25 provided, and an inclosing or protecting device, and for supporting the rack and the protecting device a common supporting bar 1 is provided, the said bar having openings 2 at its ends, and intermediate the ends for 30 receiving screws 3 or the like to connect the bar to a fixed support 4, as for instance, a wall. The bar is provided at its lower end with a single struck up perforated lug 5, and at its top the bar is provided with a pair of 35 lugs 6 and with a single lug 6^a, the said lugs 6 being spaced apart from each other at equal distances, and the lug 6^a is spaced apart from the adjacent lug 6 in the same manner. In the present instance, the lugs 6 40 and 6^a as well as the lug 5 are struck up from the material of the bar, and each of the lugs is perforated for a purpose to be presently described. The inclosing or protecting device comprises a hoop support to 45 be presently described, and a covering for the support. The lugs 6 are intended for engagement by a depending pin 7 of a sectional hoop 8—8^a, the said hoop in the present instance being elliptical or oblong, and comprising sections 8 and 8^a, pivoted together at 50 the front as indicated at 8^b. At the opposite

end each section is provided with a depending lug, and the lugs coöperate to form the pin 7 before mentioned, which engages the openings of the lugs 6. The pin 7 is designed to pass through the openings of the lugs 6 to support the hoop with its plane perpendicular to the bar 1. The rack or closed supporting bracket is also connected with the bar. The opening of the lug 6^a is 60 designed for engagement by a hook 9 on the upper end of an inclined brace 10, the lower end of the brace being received between the arms 11 of a fork on the forward end of a supporting rod 12, and pivoted thereto by 65 a pin 11^a. The rod 12 has an angular pin or lug 13 at its rear end, and the said pin is designed to engage an opening of the lug 5 at the lower end of the bar 1. The rod 12 is 70 preferably provided with notches or grooves 75 14, the said notches or grooves being transverse to the rod and on the upper face thereof, and they are spaced apart at equal distances from each other.

The hat rack as shown in Fig. 5, comprises 80 a plate or bar 15, having at its upper end an eye 16 and having at its lower end a fork. The arms 17 of the fork extend downwardly in spaced approximately parallel relation, and each arm is bent outwardly and 85 upwardly to form a hook 18. The arms 17 of the hat rack extend on opposite sides of the brace 10 at an offset portion 19 of the said brace. This portion is offset laterally, and is inclined so that the arms 17 of the 90 hat rack will engage opposite sides of the offset portion and the hat rack will be supported in perpendicular position and prevented from swinging movement in either direction.

A covering of fabric or similar material is supported by the hoop 8. The said covering comprises a top portion adapted to fit the hoop 8, and a depending portion 21. The portion 20 is of a size to fit the hoop 100 with the portion 21 depending below the hoop. This portion is split at the front, and flaps 22 and 23 are formed at each side of the split, the said flaps being adapted and designed to lap over upon each other as 105 shown more particularly in Fig. 2.

The outermost flap 23 is provided with slots 24 at spaced intervals, and buttons 25 are secured to the flap 23 for engaging the said slots or button holes 24. The button 110 holes and the buttons extend from the top to the bottom of the portion 21, so that the

flap may be secured together from the top to the bottom.

The rod 12 is designed to support coat hangers indicated at 26, and the number that 5 may be supported thereby depends of course upon the length of the rod. Hats may be hung on the rack, either on the portion 16 or on the hooks 18, and it is obvious that any kind of garments may be supported by the 10 brace 10, the rods 12 and the rack 15—17—18. The cover 20—21 is also split at the back as indicated at 27 from the top to the bottom, in order that it may be placed in position with respect to the bar 1. Flaps are 15 provided at the split in the same manner as at the front, the flaps lapping upon each other. But one of the flaps 28 is shown, and this flap is provided with buttons 29, which engage button holes in the other flap in the 20 same manner as at the front.

The device is easily set up or taken down, after the bar 1 has been connected to the fixed support. To set up the wardrobe, the bar 1 is connected to the support by means 25 of the screws 3 or any other suitable manner, and the pin 7 of the hoop 8 is engaged with the openings of the two uppermost lugs 6. The hoop is thus supported with its plane horizontal and perpendicular to the 30 bar 1. The pin 13 of the rod 12 is now engaged with the opening of the lug 5, and the hook 9 of the brace 10 is engaged with the opening of the lug 6^a. The rod 12 is thus supported in horizontal position, and 35 braced against downward movement. The coat hangers 26 each supporting a coat 30 are engaged with the rod 12, and the hat rack is arranged as shown in Figs. 1 and 3, the arms 17 of the rack being engaged on 40 opposite sides of the offset portion 19.

The covering may be placed before or after the garments have been placed, since it is obvious that the garments may be passed through the openings at the front. After 45 all have been placed, the flaps 22 and 23 are buttoned together, and the garments are perfectly protected from dust and the like. To

disassemble the device it is only necessary to disengage the buttons of the covering and to remove the same. Afterward the hoop 50 8—8^a is disengaged from the lugs 6, the hat rack is removed from the brace 10, and the brace and the rods 12 are disengaged from the bar 1. If it is desired to remove the bar 1 this will also be done. When the parts 55 have been removed they may be packed in small compass for transportation or storage. The wardrobe may also be used in different places, by providing a bar 1 in each room for instance. 60

I claim:—

1. A device of the character specified, comprising a supporting bar having means whereby it may be secured to a fixed support, having at its upper end a laterally 65 extending perforated lug, a sectional hoop comprising similar sections pivoted together at one end and each provided with a lateral pin at the other end, said pins being adapted to engage the opening of the lug to support 70 the hoop in a position perpendicular to the bar, and a covering comprising a top shaped to fit upon the hoop and having a depending portion, said portion being split at the front and the rear and having lapping flaps 75 provided with fastening means.

2. A clothes supporting bracket or rack, comprising a supporting bar having perforated lugs, a rod having an angular pin for engaging one of the lugs, a brace pivoted to 80 the other end of the rod and having a hoop for engaging another lug, and a plate having at its upper end an eye and having at its lower end a fork, the arms of which are adapted to engage astride the brace, each 85 arm having an outwardly extending hoop, and the brace having a laterally offset portion at the fork for engagement by one of the arms of the fork to hold the plate from movement longitudinally of the brace.
